UNITED STATES PATENT OFFICE.

GEORGE M. CRAWFORD, OF PITTSBURGH, PENNSYLVANIA.

DEVELOPING-TRAY.

1,135,503.

Specification of Letters Patent. Patented Apr. 13, 1915.

Application filed June 8, 1914. Serial No. 843,400.

To all whom it may concern:

Be it known that I, GEORGE M. CRAWFORD, citizen of the United States, and a resident of Pittsburgh, in the county of Allegheny and State of Pennsylvania, have invented a new and useful Improvement in Developing-Trays; and I do hereby declare the following to be a full, clear, and exact description thereof.

10 My invention relates to developing devices for use in connection with photographic negatives or plates, and has for its object to provide a cheap, simple and efficient mechanical device which will automatically do 15 the work of developing that is usually performed by hand devices through the constant moving of the trays in order to keep the liquids used in developing stirred up or moving, as well as such a device as will enable the plates to be seen at all times and 20 thus show their condition in the developing process.

To these ends my invention consists, generally stated, in the novel arrangement, construction and combination of parts, as hereinafter more specifically set forth and described and particularly pointed out in the claims.

To enable others skilled in the art to 30 which my invention appertains to construct and use my improved developing device, I will describe the same more fully, referring to the accompanying drawing, in which:-

Figure 1 is a top plan view of my improved developing device. Fig. 2 is a side elevation of the same, showing some of the parts in section. Fig. 3 is a cross-section of the tray on line 3—3 Fig. 2.

Like symbols of reference herein indicate 40 like parts in each of the figures of the drawing.

As illustrated in the drawing, my improved developing device is shown at A, in which 1 represents the tray supported upon 45 the legs or standards 2 and provided with the reservoir 3 at one end of the same, having its inner wall 4 forming the end of said tank perforated across the width of such tank as at 5. Leading from the other end 50 of the tank 1 is the suction pipe 6, which is funnel shaped at its connection with said tank, as at 7, and has a strainer or perforated cover 8 over the same and within the bottom 1' of said tank. This pipe 6 extends

horizontally under the tray and leads to and 55 beyond the front end of said tray where it extends upwardly and vertically and connects with any suitable pumping device such as the lower end of the cylinder of any ordinary force pump B. A discharge pipe 9 60 leads from the cylinder 10 of the pump B and connects with the reservoir 3 on the tank 1 by branch pipes 9' on each side of the same.

The pump B as shown is hand operated 65 from the handle 10', which is connected to a shaft 11 mounted in the standard 12, and a pinion 13 on said shaft meshes with a gear wheel 14 on a shaft 15 mounted in said standard above the shaft 11, while such shaft 70 is connected through suitable means 16 with a piston rod 17 and such rod connects with a piston (not shown) in the cylinder 10.

The use and operation of my improved developing device is as follows: The negatives or plates a to be developed are laid in the tray 1 and upon the removable rests 19 and then such rests carrying such plates are placed within the tank by fitting along each side of the same. The rests 19 are provided 80 with raised portions 20 at intervals in the same for the purpose of separating such plates a when in position thereon for developing and to form spaces or openings 18 between the plates, so that such plates may be 85 removed at any time by placing the fingers under the same through said openings. The developing fluid is placed within the tray 1 and such fluid is of sufficient quantity to extend slightly over the plates a and fill up the 90 suction pipe 6, so that such fluid can be circulated and mixed, as hereinafter described, and with said plates now in position on the rests 19 in such tray, the device will be ready 95 for the developing of such plates. This developing process is accomplished in the following manner: The handle 10' is turned with the resultant reciprocation of the piston on the piston rod 17. In this connection it will of course be apparent that the piston 100 rod 17 is actuated by the handle 10' through the medium of the gears 13 and 14 and the connecting means 16. As the piston is thus raised and lowered in the cylinder 10, the fluid in the tray 1 will be pumped or forced 105 therefrom through the suction or inlet pipe 6 into the said cylinder, and thence through the discharge pipe 9 and its branches 9' con-

necting such cylinder, into the reservoir 3 and thence into said tray through the perforated portion 5 in the inner wall 4 of said reservoir, so that there will be a circulation of the fluid in such tray and over and around the plates *a* therein, while such perforated wall will prevent the fluid as pumped from rushing into the tray from the reservoir to injure the plates and thereby permit them to be evenly and properly developed.

If desired, any form of a pump such as centrifugal, rotary, etc., can be used, and if desired, any operating or fluid operating device other than the hand device can be connected to the pump while various other modifications and changes in design, application, construction, and operation of my improved developing device can be made, without departing from the spirit of the invention, or sacrificing any of its advantages.

It will thus be seen that my improved developing device can be used in connection with plates, negatives, films, slides or other objects in developing work and by using a subdued light such objects can be seen at any time while in the process of developing, and if desired, the operator need only be required to look after the proper development of the plates, etc., where the device is made power driven. It will also be seen that in the use of my improved developing device the constant circulation of the developing fluid keeps such fluid stirred up at all times so that there is no settling, while a constant mixture of the fluid will be maintained, to render it uniform as to strength and thus making uniform work on the plates, etc. It will further be seen that in the use of my improved developing device the perforated wall in the reservoir will tend to break the effect of the force of the liquid after leaving the pump, and will cause the fluid to have a constant, even and smooth flow across and around the plates and not intermittently, thus retarding the flow of the liquid to some extent and avoiding the spoiling of the plates by too great a pressure.

What I claim as my invention and desire to secure by Letters Patent is:—

1. A device for treating photographic plates and the like, comprising a tray for containing a plate-affecting fluid, said tray being adapted for the reception of a plate horizontally therein so as to be immersed in the fluid, and means for withdrawing the fluid at one part of said tray and re-introducing it at another part, whereby a continuous circulation of the fluid is maintained about the plate immersed therein.

2. A device for treating photographic plates and the like, comprising a tray for containing a plate-affecting fluid, said tray being adapted for the reception of a plate horizontally therein so as to be immersed in

the fluid, and a pump having its inlet and outlet connected with said tray, whereby, when said pump is operated, a continuous circulation of the fluid is maintained about the plate immersed therein.

3. A device for treating photographic plates and the like, comprising a tray for containing a plate-affecting fluid, said tray being adapted for the reception of a plate horizontally therein so as to be immersed in the fluid, and said tray having a reservoir therein communicating with the remainder thereof, and means for withdrawing the fluid from said tray outside said reservoir and re-introducing the fluid into said reservoir, whereby a continuous circulation of the fluid is maintained about the plate immersed therein.

4. A device for treating photographic plates and the like, comprising a tray for containing a plate-affecting fluid, said tray having means therein for supporting plates horizontally above the bottom thereof and immersed in the fluid, and means for withdrawing the fluid at one part of said tray and introducing it at another part, whereby a continuous circulation of the fluid is maintained about the plate immersed therein.

5. A developing device comprising a tray for the developing fluid, a reservoir at one end of said tray, means for holding the plates to be developed within the tray and fluid, and pumping means for discharging said fluid into said reservoir to circulate the developing fluid therefrom through the tray and around the plates, said reservoir having a perforated wall to discharge the fluid into said tray.

6. A developing device comprising a horizontal tray for the developing fluid, means for holding the plates to be developed horizontally within the tray and fluid and above the bottom of the tray, means to separate such plates, and means for circulating the developing fluid around the plates.

7. A developing device comprising a horizontal tray for the developing fluid, rests for holding the plates to be developed horizontally within the tray and fluid and above the bottom of the tray, means to separate such plates, and means connected to the tray for circulating the developing fluid around the plates.

8. A developing device comprising a horizontal tray for the developing fluid, rests for holding the plates to be developed horizontally within the tray and fluid and above the bottom of said tray, raised portions between said plates to separate the same, and means connected to the tray for circulating the developing fluid around the plates.

9. A developing device including a tray adapted for the reception of fluid and plates immersed in said fluid, said tray having fluid inlet and outlet members, and means

connected with the inlet member for supplying a developing fluid to the tray, said means being also connected to the outlet member and being operable for effecting a continuous circulation of the fluid through the tray and around the plates immersed in the fluid.

In testimony whereof, I, the said GEORGE M. CRAWFORD, have hereunto set my hand.

GEORGE M. CRAWFORD.
